UNITED STATES PATENT OFFICE.

FREDERICK A. LIPPERT, OF CHICAGO, ILLINOIS, ASSIGNOR TO WENBORNE-KARPEN DRYER CO., OF CHICAGO, ILLINOIS, A CORPORATION OF WEST VIRGINIA.

DRYING-ROOM.

1,303,078.

Specification of Letters Patent.

Patented May 6, 1919.

Application filed April 22, 1916. Serial No. 92,868.

To all whom it may concern:

Be it known that I, FREDERICK A. LIPPERT, a citizen of the United States of America, and a resident of Chicago, county of Cook, 5 and State of Illinois, have invented certain new and useful Improvements in Drying-Rooms, of which the following is a specification.

This invention relates to kilns for drying 10 various materials and particularly for drying, oxidizing, or hardening coatings of paints or varnishes, applied to articles which are placed in or caused to pass through the kiln.

15 Objects of the invention are to provide an improved arrangement for heating and circulating air in the kiln; and to provide an arrangement of this kind which will be practical and efficient even when the ends of the 20 kiln remain more or less open to permit the continuous inward and outward passage of articles being treated.

The drawing shows an interior perspective view of a kiln constructed according to 25 this invention, the front end being a cross section. Kilns or ovens for doing the class of work for which the present kiln is designed usually comprise structures which must be closed during operation to prevent 30 the escape of heat and the disturbance of the proper operating conditions by the inflow of cold air from without. In the form shown, the present kiln comprises an elongated structure more or less open at its ends, and 35 preferably provided with tracks on the floor for guiding trucks which may be continuously or intermittently drawn along by an endless chain or belt. Spaced inwardly from the outer side walls of the kiln and running 40 parallel therewith, are partitions or walls extending upwardly from the floor, but not reaching to the roof of the kiln, and in the spaces so provided at the sides of the drying chamber are heating means for heating the 45 air and causing it to flow upward in said spaces and over the inner walls. At the lower parts of said inner walls are two sets of registers serving as air outlets. The outlets adjacent to the floor communicate with 50 the heating spaces and the outlets located in a plane above said first-mentioned outlets communicate with air outlet conduits leading to one or more common air stacks or chimneys. By this arrangement, the air 55 which is supplied to the kiln flows inwardly

from the ends along the floor, then through the lower set of registers, then upwardly around the heating coils and over the upper edges of the inner walls, then downwardly in the drying chamber to the level of the second 60 set of registers through which it is drawn out by the draft of the chimneys or the outlet stacks. It may be seen that, by this arrangement, there is a shallow lower stratum of comparatively cold air flowing 65 along the floor and extending up to the level of the lower outlet registers, being the space occupied by the trucks which support the articles being dried, and an upper and deeper stratum of heated air which extends 70 throughout the drying space. By regulating a damper in the outlet vent, more or less of the air may be recirculated through the kiln.

The outer walls 1 of the kiln are preferably insulated, the insulation 4 being shown in the drawing by a conventional section to represent air cell asbestos. These walls are preferably manufactured in sections which may be quickly mounted and secured together. The roof 6 is similarly constructed in sections, and the corner formed by the roof and the side walls 1 may be occupied by inclined sections for the purpose of directing the air flowing upwardly at the sides of the kiln toward the center of the same. The inner walls 8 extend upwardly from the floor 9 to within a foot or two of the roof 6. Heating coils 10 are located in the spaces 11 between the walls 1 and 8 and supplied with 75 a heating medium through the connections 12 to the transversely extending pipes 13 near the roof of the kiln and leading into a common supply pipe 14. The heating coils at each side are also connected to a common return pipe 15 located near the floor. Outlet registers 16 and 17 are located in different horizontal planes, and in the form shown there are the same number of each and the outlets 17 are directly above the outlets 16 80 though this is not essential since the air entering the outlets 16 naturally spreads over the floor of the heating chambers before becoming heated and rising.

The outlet conduits 18 lead from the registers 17 to a common outlet vent or chimney 19. The latter may be provided with a damper 20, whereby the flow of air out of the kiln may be controlled and the air may be caused to recirculate through the drying 105 110

chamber to a greater or less extent, as it is alternately heated and chilled by contact with the heating coils and the articles being treated.

5 A chain belt 21 extends along the middle line of the floor of the drying chamber, and is guided by suitable rollers between the guards 22. Tracks 23 are secured to the floor at each side of chain 21. The trucks 10 for carrying the articles to be treated are attached to the chain 21 and rolled along the tracks from end to end of the kiln. The ends of the kiln are partially closed by permanent walls 24 and hinged doors or flaps 15 25, these flaps being engaged and swung on their hinges as articles treated pass through the ends of the kiln. In the operation of the kiln, trucks are drawn through the same at the required speed by the chain belt 21 to 20 which the trucks are secured. The articles thereon in entering the kiln, engage the hinged doors 25, rocking them out of the way as they enter the kiln. The lower stratum of cold air prevents injury to the 25 trucks in case the same are made of wood or other material liable to injury through becoming over dry. The flow of air is always inward and, therefore, the ends of the kiln may be more or less open and such flow 30 of air is duly limited since the open spaces at the ends of the kiln are always more or less blocked by the trucks and articles entering and leaving the kiln. The areas of the air inlet openings at the ends of the kiln 35 should be so proportioned as to supply the proper amount of fresh air to suit the needs of the apparatus and limit the depth of the stratum of cold air on the floor. If the cold air extends to a level of the tops of the lower 40 registers, there will be no recirculation of air, and if it extends to the tops of the upper registers it would tend to completely choke off all air movement. It is not essential that the cold air inlets be at the ends 45 of the drying room, but the advantage of having them at the ends is obvious in view of the fact that this permits of the continuous inward and outward passage of articles without unduly disturbing the air conditions within the drying chamber.

50 Although but one specific embodiment of this invention has been herein shown and described, it will be understood that numerous details of the construction shown may 55 be altered or omitted without departing from the spirit of this invention as defined by the following claims.

I claim:

1. In an apparatus of the class described, the combination of an elongated drying chamber, means for conveying articles to be dried lengthwise through said drying chamber, means partly closing the ends of said drying chamber and formed to provide an opening approximating in shape and dimensions the silhouette of the articles to be dried and the conveying means therefor, and means for causing heated air to circulate through said drying room transversely to the length thereof.

2. In an apparatus of the class described, the combination of an elongated drying chamber, means for conveying articles to be dried lengthwise through said drying chamber, means partly closing the ends of said drying chamber and formed to provide an opening approximating in shape and dimensions the silhouette of the articles to be dried and the conveying means therefor, said means including a swingable section normally extending across the path of the articles to be dried and adapted to be swung out of such path through the passage of said articles.

3. A drying kiln, comprising an elongated structure having side walls and a roof and open ends, inner side walls spaced inwardly from said first mentioned side walls and having openings therein near the tops and bottoms thereof, heating coils located in the spaces between said side walls, air outlets in said inner side walls located above said bottom openings, and outlet flues located in said spaces between the side walls and communicating with said air outlets.

4. A drying kiln, comprising an elongated structure having side walls and a roof and open ends, inner side walls spaced inwardly from said first mentioned side walls and having openings therein near the tops and bottoms thereof, heating coils located in the spaces between said side walls, air outlets in said inner side walls located above said bottom openings, and outlet flues located in said spaces between the side walls and communicating with said air outlets, the ends of said drying room being provided with hinged flaps which may be engaged and pushed aside by articles passing into and out of the drying room.

Signed at Chicago this 17th day of Apr., 110 1916.

FREDERICK A. LIPPERT.
